(57) **CLAIM**

The ornamental design for a set of a drawer body and a drawer outer frame, as shown and described.

DESCRIPTION

FIG. 1 is a front, right, and top perspective view of a set of a drawer body and a drawer outer frame, showing my design.

FIG. 2 is an another perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 1 outlined by dot-dash broken line.

FIG. 10 is a front, right, and top perspective view of the set of the drawer body in another state and the drawer outer frame in FIG. 1.

FIG. 11 is a front, right, and top perspective view of the set of the drawer body in another state and the drawer outer frame in FIG. 1.

FIG. 12 is a front, right, and top perspective view of the set of the drawer body and the drawer outer frame in FIG. 1 in an assembled state.

FIG. 13 is an another perspective view thereof.

FIG. 14 is a front elevation view thereof.

FIG. 15 is a rear elevation view thereof.

FIG. 16 is a left side elevation view thereof.

FIG. 17 is a right side elevation view thereof.

FIG. 18 is a top plan view thereof.

FIG. 19 is a bottom plan view thereof.

FIG. 20 is a front, right, and top perspective view of the set of the drawer body and the drawer outer frame in FIG. 10 in an assembled state; and,

FIG. 21 is a front, right, and top perspective view of the set of the drawer body and the drawer outer frame in FIG. 11 in an assembled state.

(Continued)

The broken lines in the drawings depict portions of the set of the drawer body and the drawer outer frame that form no part of the claimed design. The dot-dash broken line circles in FIG. 1 and FIG. 9 are for the purpose of illustrating the boundary of the enlarged view and forms no part of the claimed design.
